(57) CLAIM

The ornamental design for a furniture handle, as shown and described.

DESCRIPTION

FIG. 1 is a back view of a furniture handle showing my new design;

FIG. 2 is a top plan view thereof, wherein non-uniform patterns of dots are used to indicate surface stippling;

FIG. 3 is a front elevation view thereof;

FIG. 4 is a right side view thereof, the left side view being a mirror image thereof; and,

FIG. 5 is a bottom plan view thereof.
